C. R. YOUNG

LOADING COIL CASE AND THE LIKE

Original Filed Dec. 28, 1918

UNITED STATES PATENT OFFICE.

CHARLES R. YOUNG, OF BLOOMFIELD, NEW JERSEY, ASSIGNOR TO WESTERN ELECTRIC COMPANY, INCORPORATED, OF NEW YORK, N. Y., A CORPORATION OF NEW YORK.

LOADING-COIL CASE AND THE LIKE.

Original application filed December 28, 1918, Serial No. 268,765. Divided and this application filed July 9, 1923. Serial No. 650,321.

To all whom it may concern:

Be it known that I, CHARLES R. YOUNG, a citizen of the United States, residing at Bloomfield, in the county of Essex, State 5 of New Jersey, have invented certain new and useful Improvements in Loading-Coil Cases and the like, of which the following is a full, clear, concise, and exact description.

0 This invention relates to cases for loading coils, transformers, and the like and more particularly to sealing and protecting such apparatus. One of its objects is the production of a casing for use in tropical countries, which will protect the coils or other apparatus mounted therein from injury by moisture or insects, when such apparatus is installed on poles or in other exposed locations.

20 Another object is to provide a novel method of bringing the coil terminals to the outside of the case in such a manner that the use of leading-in wires covered with rubber or similar insulation, which would be 25 quickly destroyed by insects or would rapidly deteriorate under the extreme climatic conditions met in tropical countries, will be unnecessary.

Both of these objects are attained by the 30 use of novel moisture and insect proof two-piece insulating bushings for the openings in the case through which connection between the coil and the associated exterior apparatus or line is made, and consisting 35 of an outer cylindrical member and an internal washer member placed on opposite sides of the casing wall. Extending through this bushing is a conducting bolt which serves as the electrical connection between 40 the coil and the outside of the case. Sealing means consisting of a novel form of insect proof leather and lead washer is provided, thereby preventing leakage of the insulating compound with which the case is filled.

45 The invention will be better understood by reference to the accompanying drawing wherein:

Fig. 1 is a vertical sectional view on line 1, 1 of Fig. 2 of a case for loading coils, 50 embodying said invention, and Fig. 2 is a sectional plan view of the case on line 2, 2 of Fig. 1.

The case 1 constructed of any desired ma-

terial, such as iron, is arranged to receive a loading or toroidal shaped coil 2 adapted to 55 be supported therein in any desired manner such as on a spindle or axial support 3, rigidly mounted within and preferably secured at its lower end to the bottom of the case. This spindle is preferably of non- 60 magnetic material such as wood, and is maintained in an upright rigid position by a spider 4, which is secured to the inner wall of the case by clamping screws 5. The case is preferably constructed with an annular outwardly-projecting flange 6 to which the cover 7 is secured by the bolts 8, a corrugated copper gasket 7^a coated with 65 red lead being interposed between said cover and flange.

The bottom of the case is provided with 70 openings 9 into each of which one end of a cylindrical insulating bushing member 10, made of any suitable material such as porcelain, is inserted. Overlying the outer periphery of the openings 9, are annular shoulders 11 formed integrally with the bushings 10. Interposed between these shoulders and the casing 2, is a compound seal made up of a resilient washer 12 and 75 a non-resilient compressible washer 13. The washer 12 is preferably of leather, and the washer 13 of lead which serves to shield the leather washer from the attacks of insects. As a further protection it is preferable to 80 impregnate the leather washer with chlorinated naphthalene, as experience has shown that insects are repelled by it. An opening 85 14 extends axially through the bushing member 10 and is provided with an internal annular shoulder or seat 15. The outer or 90 lower end of these bushings is provided with "double petticoats" 16, formed integrally therewith, thereby increasing the external surface of the insulator at this point 95 and increasing the insulation by minimizing what is known as surface leakage.

Surrounding the bushings 10 is a housing or shed 16^a open at the bottom, and formed by downwardly extending the side 100 walls of the case.

Inside the case and formed integrally with the bottom are a plurality of bosses 17 which surround the periphery of the 105 openings 9. Overlying said openings and coaxial with the outer cylindrical members

10 are located insulating washer members 18 preferably made of the same material as the outer bushing members 10. These washer members are provided with an opening 19 and a diametrical slot 20, which is formed in their upper or top side. In the bottom side of said washer members are formed radial slots 21, which coincide with but are slightly larger in cross-section than the bosses 17. Lying in the diametric slots 20 are terminal lugs 22, the bolt holes of which coincide with the openings 19. Extending axially through the openings in the terminal lugs and the two-piece bushing 18 and 10, 15 is a bolt 23 having a square head 24, its other end being screw-threaded and provided with round nuts 25, a brass washer 26, and a leather washer 27 impregnated with a wax compound containing an insect repelling element which seats on the annular shoulder 15. In practice, it is found desirable to solder the head 24 of the conducting bolt 23 to the terminal lug and, to further prevent insects from attacking the leather 20 washer 27, the space surrounding said washer 27, the space surrounding said leather washer 27, and the brass washer 26 is filled with molten lead 39.

In order to provide suitable mounting facilities for the lightning arrester equipment required for installation with loading coils of the type described, a compartment or housing 30 is provided, formed at the side of and integrally with the case, and having a hinged door 31, in which are mounted vacuum tube lightning arresters consisting of a porcelain or other insulating base 32, contact clips 33 and 34, and a vacuum arrester tube 35.

The terminals of these arresters are brought inside the case by an arrangement of insulating bushings, sealing washers and conducting bolts similar to those just described, except that the cylindrical members of this group of bushings on which the arrester bases rest, as shown, are not potted coated, and that the outer or threaded portion of the conducting bolts are connected with the contact clips 33 and 34 by means of nuts.

50 After the coils are in place and the windings connected with the terminal lugs by any suitable means, preferably rubber insulated wire, the case is filled to about the bottom of the spider 4, with a suitable sealing compound such as resin and resin oil. This compound will flow into and fill the spaces between the casing wall, the bushings and the conducting bolts, but will not pass the leather washers 12 and 15 which prevent the compound from leaking to the outside of the case.

The cover is then secured in place and through an opening 36 therein, hot asphaltum is poured until the case is completely filled. A plug 38 coated with red lead is

then tightly screwed into the opening, thereby rendering the case impervious to air and moisture.

Connections with the line are made by soldering the line wires into the slotted ends 70 of the screws 29, which are held in contact with the end of the conducting bolt 23 by means of the sleeve member 28. Hooks 43 and 40 formed integrally with the case 1 are provided for the purpose of supporting 75 the case from the pole or other supporting fixture, through the medium of U-shaped hangers 41, 42.

The invention described and claimed herein has been divided out of my application Serial No. 268,765, filed December 28, 1918.

The invention claimed is:

1. The combination with a casing for loading coils and the like, having insulating bushings having coaxial parts interior and exterior of said casing, and conducting means retained thereby extending through the wall of said casing, of sealing gaskets between the exterior part of said insulating bushing and said casing and between said conducting means and bushing, and a washer concentrically surrounding said gasket, and means for making said washer practically impervious to insects.

2. The combination with a casing wall 90 having an opening therethrough, of a two-part insulating bushing member having an opening extending axially therethrough, one end of the outer part of said member extending into said opening in the casing wall 100 and the other part within said casing, the outer part of said member being provided adjacent said end with a shoulder overlying the periphery of said opening of the casing wall, a compound sealing gasket comprising 105 a resilient washer and a non-resilient compressible washer concentrically arranged around said opening, and a conducting bolt clamping the parts of said member together.

3. The combination with a casing wall 110 having an opening therethrough, of a two-piece insulating bushing comprising an outer member and an inner member, said outer member having one end extending into 115 said opening in the casing wall, and having a shoulder adjacent said end overlying the periphery of said opening, said inner member resting on the opposite side of said casing wall, bosses surrounding the periphery of said opening in the casing wall 120 and cooperating with the said inner member to prevent it from turning, a conducting bolt extending through said bushing and casing wall, and means co-acting with said bolt for holding said bushing members and casing wall in assembled relation.

4. The combination with a casing wall having an opening therethrough, of a two piece insulating bushing comprising an external member having its inner end extending into 130

said opening in the casing wall and provided adjacent said inner end with a shoulder overlying the periphery of said opening in the casing wall, petticoats on the outer end 5 of said external member, an internal member having slots in the side adjacent to the casing wall and coinciding with bosses surrounding the periphery of the said opening in the casing wall, and a conducting bolt 10 extending through the opening in said bushing members, and means co-acting with said bolt for holding said bushing members and casing wall in assembled relation.

5. The combination with a casing wall 15 having an opening therethrough, of a two piece insulating bushing comprising an outer member and an inner member, said outer member having an opening extending axially therethrough and provided with an 20 internal shoulder, one end of said outer member extending into said opening in the casing wall and provided adjacent said end with a shoulder overlying the periphery of said opening in the casing wall, petticoats 25 on the other end of said outer member, sealing gaskets between said shoulder and the periphery of said opening in the casing wall, said inner member having radial slots in the

side adjacent to the casing wall, bosses on said casing wall surrounding the periphery 30 of the opening therein and coinciding with but not completely filling said radial slots, a conducting bolt extending axially through said bushing, sealing gaskets surrounding said conducting bolt and bearing on said internal shoulder, means co-acting with said bolt for holding said bushing members, gaskets and casing wall in assembled relation, and insulating compound between said conducting bolt bushing members and casing 40 wall.

6. The combination of a casing having a wall, an opening therein, an electrical conductor comprising a bolt passing through said opening, a disc inside of said casing 45 having an aperture to receive said bolt, an insulating bushing outside of said casing having a plurality of shoulders and an aperture to receive said bolt, a washer between one of said shoulders and said wall and a 50 second washer between said bolt and said bushing, and a nut on said bolt for clamping said parts.

In witness whereof, I hereunto subscribe my name this 3 day of July A. D., 1923.

CHARLES R. YOUNG.
